UNITED STATES PATENT OFFICE.

JOHN J. KLEIN, OF SCRANTON, PENNSYLVANIA.

CRAPE-HOLDER.

1,018,326.

Specification of Letters Patent.

Patented Feb. 20, 1912.

Application filed July 22, 1911. Serial No. 639,996.

To all whom it may concern:

Be it known that I, JOHN J. KLEIN, a citizen of the United States, residing at Scranton, in the county of Lackawanna and State of Pennsylvania, have invented new and useful Improvements in Crape-Holders, of which the following is a specification.

An object of the invention is to provide a device for attachment to a door or the like for supporting a crape usually displayed by the undertaker in case of a death, the crape being neatly and gracefully retained in supporting position.

For the purpose mentioned, use is made 15 of a flexible attaching plate, a supporting plate for slidably receiving the attaching plate and adapted to frictionally retain the same in engagement therewith and a face plate removably connected to the supporting 20 plate and upon which the body of the crape is secured, the attaching plate being provided with means for connecting the same to a door or the like to support the crape.

Reference is to be had to the accompanying 25 drawings constituting a part of this specification, in which similar characters of reference denote corresponding parts in all the views, and in which—

Figure 1 is a side elevation showing my 30 device applied. Fig. 2 is a front elevation of my device, the crape being detached therefrom to disclose the face plate, parts being broken away to disclose the underlying structure. Fig. 3 is a rear elevation, 35 the attaching plate being removed from the supporting plate. Fig. 4 is a vertical sectional view of the face plate and supporting plate with the attaching plate connected to the supporting plate. Fig. 5 is 40 a perspective view of the attaching plate. Fig. 6 is a horizontal sectional view taken on the line 6—6 in Fig. 5, looking in the direction of the arrow.

Referring more particularly to the views, I 45 provide a face plate 10 consisting preferably of a flexible material to which a crape 11 can be conveniently sewed or otherwise secured and the face plate 10 is connected to the front side of a supporting plate 12 by cotter pins 13 passed through the supporting 50 plate and the face plate and having their outer ends bent in opposite directions to rigidly retain the face plate on the supporting plate. The supporting plate 12 preferably consists of an integral piece of material having portions stamped therefrom

and bent rearwardly on the body of the supporting plate to form inclined guides 14, the said guides having apertures 15 formed therein for a purpose that will be herein-after more fully disclosed. An attaching plate 16 is formed of an integral piece of material and has edges 17 thereof extending outwardly from the attaching plate and formed at an incline to the vertical axis of the plate, the said edges being adapted to slide in the guides 14 of the supporting plate 12 with flanges 18 formed on the edges 17, the said flanges being received in the apertures 15 in the guides 14. The attaching 70 plate 16 consists more substantially of a body portion 16^a having sides 16^b bent laterally to the body portion 16^a with the edges 17 bent laterally to the side 16^b so that the said edges will be in parallel relation to the body portion 16^a, but will be offset therefrom as shown in Fig. 5, the sides 16^b being preferably made flexible so that when the attaching plate is engaged with the supporting plate, the flexibility of the sides 16^b will 80 rigidly retain the attaching plate in engagement with the supporting plate. A plurality of pins 19 are extended from the outer side of the attaching plate 16 and a swivel plate 20 is mounted on the inner side 85 of the attaching plate 16, the swivel plate being provided at the ends thereof with slots 21, through which are passed securing pins 22 secured to the body portion 16^a to slidably retain the swivel plate on the attaching plate. An aperture 23 is formed 90 in the swivel plate 20 and a swivel 24 provided with a handle 25 and a threaded end 26, is passed through the aperture 23 and extends through the attaching plate 16, a retaining plate 27 being secured to the swivel 24, between the body portion 16^a and the swivel plate 20 to retain the swivel 24 in engagement with the swivel plate 20 as 95 will be readily understood.

In the use of my device the attaching plate 16 is pressed against the outer side of a door 28 and by turning the handle 25, the threaded end 26 of the swivel 24 will grip the door to rigidly hold the attaching 105 plate 16 on the door; the pins 29 being provided to extend into the door and prevent any turning of the attaching plate. The supporting plate 12, having the face plate 10 secured thereto, with the crape 11 conveniently sewed or otherwise secured to the face plate, is now engaged with the attach- 110

ing plate so that the edges 17 will be received in the guides 14, the flanges 18 being received in the apertures 15 of the guides 14 and the flexibility of the sides 16^b of the attaching plate 16 will frictionally retain the supporting plate in engagement with the attaching plate, while the incline of the guides 14 and the edges 17 will prevent the supporting plate from moving downwardly on the attaching plate and becoming disengaged therefrom.

With a device of the character described, the crape can be quickly and gracefully positioned on a door or the like and will be rigidly retained from being blown away or torn by a storm.

Having thus fully described the invention, what I claim as new, is:

1. In a device of the class described, a face plate adapted to support a crape, a supporting plate, means for rigidly securing the face plate to the supporting plate, inclined guides formed on the supporting plate and provided with apertures therein, an attaching plate provided with inclined edges adapted to operate in the guides of the supporting plate, flanges formed on the inclined edges of the attaching plate and adapted to be received in the apertures in the said guides, a swivel plate slidably mounted on the attaching plate and a swivel rotatably mounted on the swivel plate and extending through the attaching plate for rigidly securing the attaching plate to a door or the like.

2. In a device of the class described, a supporting plate, a face plate for engagement with the front side of the supporting plate, inclined guides formed on the rear side of the supporting plate, an attaching

plate having inclined edges for engagement with the guides of the supporting plate and means for connecting the attaching plate to a door or the like.

3. In a device of the class described, a supporting plate adapted to support a crape, inclined guides formed on the supporting plate, an attaching plate for slidable engagement with the inclined guides of the supporting plate and a swivel mounted on the attaching plate for connecting the attaching plate to a door or the like.

4. In a device of the class described, a supporting plate adapted to support a crape, inclined guides formed on the supporting plate, an attaching plate having inclined edges for slidable engagement with the guides on the supporting plate and means on the attaching plate for connecting the same to a door or the like to retain the supporting plate in supporting position.

5. In a device of the class described, a supporting plate, a face plate secured to the supporting plate, and adapted to have a crape connected thereto, apertured guides formed on the supporting plate, an attaching plate for slidable engagement with the guides on the supporting plate, flanges formed on the attaching plate and adapted to be received in the apertures in the said guides when the attaching plate is slidably engaged with the supporting plate and means for connecting the attaching plate to a door or the like.

In testimony whereof I affix my signature in presence of two witnesses.

JOHN J. KLEIN.
